UNITED STATES PATENT OFFICE.

LEWIS L. ROGERS, OF ORANGE, MASSACHUSETTS.

SHEET-GAGE FOR PRINTING-PRESSES.

1,170,994.

Specification of Letters Patent.

Patented Feb. 8, 1916.

Application filed January 28, 1915. Serial No. 4,834.

To all whom it may concern:

Be it known that I, LEWIS L. ROGERS, a citizen of the United States, and resident of Orange, in the county of Franklin and State of Massachusetts, have invented certain new and useful Improvements in Sheet-Gages for Printing-Presses, of which the following is a specification.

The present invention relates to gages for printing presses and particularly to an end-gage for a one-cylinder, two-revolution press in which the cylinder is movable up and down relatively to a horizontally reciprocating form and bed. In presses of this type, the individual sheets to be printed are usually fed by hand on a feed table against an end-gage, the sheets usually being fed in a direction substantially parallel to the axis of the cylinder, and the end-gage being so disposed as to gage the front end of the sheet, that is, the edge of the sheet which is disposed at right angles to the direction of feed of the sheet. Such a gage is, therefore, termed herein "an end-gage". In a press of this type, there are also provided suitable side gages which are designed to gage the side of the sheet, or that edge of the sheet which is parallel to the direction of feed and substantially at right angles to the edge of the sheet gaged by the end-gage.

The principal object of the invention is to provide a novel form of end-gage which is automatically movable to its working position and which is capable during its movement of so shifting the position of the sheet that it will be brought into contact with all of the side gages, thereby producing perfect registry of the sheet.

A further object of the invention is to provide an end-gage, the parts of which are constructed in a novel manner to effect the automatic movement of the gage in a simple and effective manner. Furthermore, the parts of the gage are so constructed as to render the gage reversible, that is, the gage may be used at either side of the feed table by changing the position of certain parts of the gage to adapt the same for use at the other side of the press.

The invention is illustrated in the accompanying drawings, in which:—

Figure 1 is a plan view of a portion of a printing press of the one-cylinder, two-revolution type, showing a portion of the feed table with the improved end-gage sup-

ported thereby; Fig. 2 is a broken transverse section taken on the line 2—2 of Fig. 1; Fig. 3 is a plan view of the end-gage; Fig. 4 is a side elevation of the construction shown in Fig. 3; and Fig. 5 is a horizontal section taken on the line 5—5 of Fig. 4, illustrating a detail of construction.

In the drawing, the letter A indicates a portion of the feed table of the press, the cylinder of which is indicated at B. In the type of press illustrated, that is, a one-cylinder, two-revolution press, the cylinder B moves bodily up and down, in the well-known manner, to coöperate with a horizontally reciprocating form and bed. Mounted in the cylinder is the usual rock shaft C carrying a series of grippers D for gripping the edge of the sheet and carrying it around with the cylinder, in the usual manner. The grippers D are actuated by the customary cam E carried by the end of the rock shaft and the sliding pin F actuated by the cam G.

The side gages of the press are indicated at H, and so far as the present invention is concerned, it is immaterial what the specific construction of these gages is. As the improved end-gage may be used in combination with any type of side gage, whether the same be stationary or automatically movable, the specific construction of the gages H will not be described.

In the type of press herein illustrated, the cylinder B moves up and down, as hereinbefore stated, and moves bodily with a frame I, in which is mounted the press-rod J running transversely across the press longitudinally of the cylinder. Relatively stationary upstanding portions K, of a suitable part of the press frame, carries a press-rod L, and the relative movement between the press-rod J and the press-rod L, caused by the vertical movement of the cylinder and frame I, is utilized for actuating the end-gage, as will hereinafter appear.

The end-gage itself comprises a base-plate 1 having several longitudinally disposed slots or openings 2, by means of which the base-plate 1 may be secured to the feed table by means of bolts or other suitable fastening devices 3. The slots 2 permit bodily adjustment of the base-plate 1 on the feed table A, in an obvious manner. The base-plate 1 has cast integral therewith, a couple of upstanding portions 4 serving as bearings for a cylindrical sleeve 5, which is

longitudinally slideable in openings 6 provided in said upstanding portions 4. The sleeve 5 carries a collar 7 which is rigidly fastened to said sleeve by means of a set screw 8. The collar 7 carries an upstanding portion 9, which is centrally perforated to permit passage therethrough of a threaded adjusting rod 10, the purpose of which will be presently described. The collar 7 also 10 carries a depending lug 11 having an opening therein through which a guide rigidly carried by the rear upstanding bearing portion 4, passes. In the present instance, this guide comprises a small cylindrical pin 12, 15 on which the lug 11 is adapted to slide. By this construction, the sleeve 5 and collar 7 are absolutely held against turning movements about the axis of the sleeve 5.

Passing through the sleeve 5 and co-axially disposed with respect thereto is a stem 13, which carries, at its forward end, a block 14, through which passes a gage-rod 15 disposed substantially at right angles to the stem 13. The gage-rod 15 is adjustably 20 mounted in the block 14 and may be shifted longitudinally of itself in said block. It is held in its adjusted position by means of a set screw 16. The adjusting rod 10, hereinbefore mentioned, has a horizontally disposed portion which passes through the upward extension 9 of the collar 7, as above stated, and a downwardly directed extremity 25 17, which is rigidly secured to the block 14. Adjusting and lock nuts 18 are 30 threaded on the adjusting rod 10 and coöperate with the adjacent faces of the upstanding portion 9 to adjust the position of the rod 10 and to lock the same in adjusted position, in an obvious manner. When the rod 40 10 is so adjusted, it obviously adjusts the position of the stem 13 in the sleeve 5, and when the rod 10 is locked to the upstanding portion 9, the stem 13 is in locked relation with the sleeve 5. Under these conditions, 45 the sleeve 5, stem 13, collar 7, rod 10 and gage-rod 15 will all move bodily in unison in the upstanding bearing portions 14.

The gage-rod 15 carries, at one side of the block 14, the gage proper 19, which may be 50 of any suitable construction, but preferably consists of a block 20 through which the gage-rod 10 passes, and to which it is adjustably secured by means of the set screw 21. The block 20 has secured thereto, the 55 gage face 22 and the customary spring guard 23. The other end of the gage-rod 15 carries a block 24 adjustably secured to the gage-rod by means of a set screw 25 and carrying a roller 26, which rolls along the surface of the feed table and supports the adjacent end 60 of the gage-rod in a sufficiently elevated position to assure the gage 19 at the opposite end thereof being held in close contact with the feed table to prevent accidental slipping of the sheets under said gage. In or-

der to assure such contact of the gage with the feed table under varying conditions, there is preferably provided a vertically adjustable connection between the block 24 and the roller 26, this connection as here shown 70 comprising a stem 26' carrying the roller 26 and being adjustably secured to the block 24 within a vertical opening therein by means of a set-screw 26''. It will be noted that the gage 19 and the roller block 24 may 75 not only be adjusted to any position along the gage-rod, but they may be entirely removed and interchanged, in the manner hereinafter described.

The movement of the gage 19 to its working position is preferably effected as follows. The base-plate 1 of the gage pivotally carries a bell-crank lever 27 pivotally mounted on the base-plate by means of the removable screw 28. One arm of the bell-crank lever 85 27 engages behind the depending lug 11 of the sleeve 7, as best shown in Figs. 3 and 5, and the extremity of the other arm of the bell-crank lever lies adjacent the extremity of a guide 29, through which passes an actuating rod 30. When the rod 30 is moved longitudinally, it is obvious that the bell-crank lever will be swung around its pivot and the depending lug 11 moved to the dotted line position shown in Fig. 5. This effects a unitary movement of the collar 7, sleeve 5, rod 10 and stem 13, together with the gage-rod 15 and the gage proper 19. This movement is yieldingly resisted, however, by means of a coil spring 31 interposed 95 between the forward upstanding portion 4 of the base-plate 1 and the collar 7. This spring serves to return the parts to their normal position after each actuation of the gage. 100

The actuating rod 30 is pivotally connected at 32, (Fig. 1), to a stem 33 which telescopes into the main actuating rod 34 and is adjustably held therein by means of the set screw 35. Referring particularly to Fig. 2, it will be seen that the main actuating rod 34 is pivotally connected at 36 to a sleeve 37 loosely mounted upon the press-rod L. The relatively movable press-rod J carries a sleeve 38, which is rigidly secured to its press-rod by means of a set screw 39. The collar 38 is provided with two forwardly projecting cheeks 39' between which passes a pin or roller 40, which engages in a slot 41 provided in a rearwardly projecting portion on the sleeve 37. By this construction, it is obvious that as the cylinder B and frame I, together with the movable press-rod J, move from the dotted line position shown in Fig. 2, to the full line position, the sleeve 115 37 will be rocked or shifted from its dotted line position shown in Fig. 2 to the full line position, and the actuating rod 34 will, therefore, be shifted longitudinally to the right 120 in the drawings. This will produce a longi-

tudinal movement of the actuating rod 30 in the guide 29 and a movement of the bell-crank lever 27 to effect the movement of the gage, in the manner hereinbefore described.

5 In operation, a sheet is fed in a direction substantially parallel to the axis of the cylinder toward the end-gage until the front edge of the sheet comes into contact with the gage face of the gage. As the cylinder 10 rises, the parts of the end gage are actuated, as above described, so that the end-gage is shifted to its working position. It will be noted that the end-gage is so positioned as to engage either to one side or the other of 15 the central longitudinal axis of the sheet. As the gage, however, is adjustable with respect to the gage-rod 15 and interchangeable with respect to the roller block 24, it may be made to engage with the sheet at any point 20 along the front edge thereof. When it is made to engage with one side or the other of the front edge of the sheet, the sheet will not only be removed bodily backward, but one end thereof will be shifted in a 25 lateral direction, so that if the side edge of the sheet is not engaging with all of the side gages, the movement of the end gage will shift the sheet into proper engagement with all of the side gages. In other words, 30 as the sheet is moved by the end-gage, it has imparted thereto a slight turning movement which has the effect of bringing the side edge of the sheet into engagement with all of the side gages. It will be found that 35 there exists a certain point along the front edge of the sheet where the end-gage, if made to contact with the sheet at this point, will produce just enough turning movement of the sheet to bring the same into proper 40 contact with the side gages.

The construction of the end-gage above described not only permits of numerous adjustments, but the entire gage is reversible, that is, it may be used at the other side of 45 the feed table when it is desired to feed the sheets in a direction opposite to the direction of feed indicated by the arrow in Fig. 1. For this purpose, the bell-crank lever 27 is made reversible, so that it can be mounted 50 at the other side of the base-plate 1, a second opening 42 being provided in the base-plate for this purpose. Fig. 5 shows, in dotted lines, the position which the bell-crank lever will assume when pivotally 55 mounted at 42. The actuating rod 30 will then, of course, be made to enter the guide 29 from the other side thereof, as further indicated in dotted lines at 30' in Fig. 5. When the position of the base-plate 1 is so 60 transferred from one side of the feed table to the other, as indicated in dotted lines in Fig. 1, it will also be necessary to interchange the gage 19 and roller block 24, if it is still desirable to have the gage 19 engage 65 with the edge of the sheet to the press side

of the longitudinal center line of the sheet. The actuating sleeves 37 and 38 mounted on the press-rods may be readily shifted to their new positions indicated in dotted lines in Fig. 1, or, if desired, additional sleeves 79 may be provided at this side of the press and the original sleeves 37 and 38 left undisturbed.

Although the improved end-gage has been illustrated and described in combination with a printing-press of the one-cylinder, two-revolution type, it is obvious that it may be as satisfactorily used on other types of presses, and on machines other than printing-presses where a proper registry of 80 the sheet is necessary. Furthermore, the gage need not necessarily be used as an end-gage, as obviously it will function in the same manner if used in other relations.

Numerous modifications and changes may 85 be made in the details of construction and operation without departing from the spirit or scope of the invention, as defined in the accompanying claims.

What I claim is:—

1. In a printing press, the combination with a feed table from either end of which a sheet may be fed toward an end gage, of a base plate removably supported by the feed table at one end thereof, a movable end 90 gage associated with said base-plate, and actuating means for the gage partly carried by the base-plate, said base-plate and end gage being transferable to the other end of the feed table and certain parts of the actuating means on the base-plate being capable of being repositioned thereon to render the end gage operable in its new position.

2. In a printing press, the combination with the feed table, of a sheet gage removably supported by the feed table and comprising a base-plate, a movable gage associated with said base-plate, a bell-crank lever for actuating said movable gage, and means to actuate the bell-crank lever, said 105 bell-crank lever being transferable to a new position on the base-plate, for the purpose described.

3. The combination with the feed table of printing presses and similar machines, of a sheet gage comprising a base-plate removably secured to said feed table, a movable gage proper associated with said base-plate, and actuating means for said movable gage comprising a movable element mounted 115 on said base-plate, and means whereby said element may be transferred to a new position on said base-plate to permit the gage to be used at either side of the feed table.

4. The combination with the feed table 125 of a printing press or similar machine, of a base-plate mounted on said feed table, a movable gage proper supported from said base-plate, a rod slidably mounted on said base-plate and to which the gage is secured, 130

and a bell-crank lever pivotally mounted on the base-plate adapted to be actuated from a movable part of the machine, said base-plate with the gage, rod and bell-crank lever supported thereby being removable as a unit from the feed table, for the purpose described.

5. The combination with the feed table of a printing press or similar machine, of a base-plate removably mounted on the feed table, a movable gage proper associated with the base-plate, means for mounting the movable gage on the base-plate comprising a rod movable longitudinally with respect to the base-plate, an actuating rod movable transversely with respect to the base-plate, connecting means between said rods, and means whereby said connecting means may be pivoted to the base-plate at either one of two places in each of which the connecting means operatively connects said rods whereby the operative relation between the parts may be maintained when the base-plate is mounted at either side of the feed table.

10 6. The combination with the feed table of a printing press or similar machine, of a base-plate removably mounted thereon, a movable gage proper associated with the base-plate, actuating means for said movable gage, connecting means between the actuating means and said movable gage, and means whereby said connecting means may be pivoted to the base-plate at either of two places in each of which the connecting means operatively connects the actuating means with the movable gage to maintain the operative relation between the actuating means and the movable gage when the base-plate is mounted at either side of the feed table.

15 7. The combination with the feed table of a printing press or similar machine, of a base-plate removably mounted on said feed table, a substantially T-shaped movable gage rod mounted on said base-plate, actuating means for said gage rod, connecting means between said actuating means and the gage rod, said connecting means being transferable to a new position on the base-plate to maintain the operative relation between the actuating means and the gage rod when the base-plate is used at either side of the feed table, and a movable gage proper removably and adjustably carried by that portion of the T-shaped gage rod which is substantially parallel to the edge of the sheet to be gaged whereby said movable gage proper may be adjusted or transferred to its proper position on the gage rod when the base-plate is changed from one side of the feed table to the other.

20 8. A sheet gage for printing presses and

similar machines, comprising a base-plate, a stem mounted for longitudinal movements with respect to the base-plate, a gage rod disposed substantially at right angles to said stem, an adjustable connection between said stem and said rod to permit adjustment of the rod transversely of the stem, a movable gage proper adjustably carried by said rod, and means to actuate said rod.

25 9. The combination with the feed table of a printing press or similar machine, of a sheet gage comprising a base-plate removably and adjustably mounted on the feed table, a stem mounted for longitudinal movements with respect to the base-plate, a gage rod disposed substantially at right angles to said stem, an adjustable connection between said stem and said rod, a movable gage proper adjustably and removably carried by said rod, and operative connections between said stem and a moving part of the press for actuating the movable gage, said connections being adjustable, for the purpose described.

30 10. The combination with a printing press and the feed table therefor, of a sheet gage comprising a gage-rod, means supporting said rod at a point between the ends thereof, a gage proper carried by said rod at one end for contact with the feed table, and means co-operative with said rod at its opposite end to hold said gage in contact with the feed table.

35 11. The combination with a printing press and the feed table therefor, of a sheet gage comprising a gage-rod, means supporting said rod at a point between the ends thereof, a gage proper carried by said rod at one end for contact with the feed table, and a roller carried by said rod at its opposite end in engagement with the feed table and supporting the rod with the gage thereon in contact with said table.

40 12. The combination with a printing press and the feed table therefor, of a sheet gage comprising a gage-rod, means supporting said rod at a point between the ends thereof, a gage proper carried by said rod at one end for contact with the feed table, a roller carried by said rod at its opposite end in engagement with the feed table and supporting the rod with the gage thereon in contact with said table, and means for vertically adjusting the rod relatively to the roller adjacent its connection therewith.

45 Signed at Orange, in the county of Franklin, and State of Massachusetts, this 26th day of January A. D. 1915.

LEWIS L. ROGERS.
